UNITED STATES PATENT OFFICE.

RICHARD HENRY COTTER, OF BROOKLYN, NEW YORK.

DESIGN FOR A GAME-BOARD.

60,013.

Specification for Design.

Patented Dec. 20, 1921.

Application filed July 21, 1921. Serial No. 486,612. Term of patent 3½ years.

To all whom it may concern:

Be it known that I, RICHARD H. COTTER, a citizen of the United States, residing at New York, borough of Brooklyn, in the county of Kings and State of New York, have invented a new, original, and ornamental Design for a Game-Board, of which the following is a specification, reference being had to the accompanying drawing, forming a part thereof.

The accompanying drawing is a perspective view of my new and original game board.

I claim:

The ornamental design for a game board, as shown.

RICHARD HENRY COTTER.
